PUMP FOR FLANGE LUBRICATORS

Filed April 7, 1928

UNITED STATES PATENT OFFICE

EMERY C. HOWERTON AND ANDREW BERGLIN, OF DENVER, COLORADO, ASSIGNEES
OF ONE-THIRD TO GEORGE C. CALLAHAN, OF DENVER, COLORADO

PUMP FOR FLANGE LUBRICATORS

Original application filed September 26, 1927, Serial No. 221,922. Divided and this application filed April 7, 1928. Serial No. 263,209.

This invention relates to improvements in flange oilers of the general type employed in the lubrication of the flanges of the wheels of locomotives.

Locomotives and other vehicles that run on rails are provided with flanges for the purpose of keeping the vehicles on the track. Even when the track is perfectly straight, the flanges will contact with the rails from time to time and in passing around curves the pressure between the flanges and the rails often becomes very high. If the flanges are not lubricated, they will wear very fast and besides this the great amount of friction between the unlubricated flange and the rail has a tendency to make the wheels "climb" the rail and to thereby cause wrecks.

It is the object of this invention to produce a lubricating device that shall be so constructed that it is positive in its action and which will operate to lubricate the flanges whenever the locomotive is operating and which will cease functioning whenever the locomotive stops.

It is the object of this invention to produce a pump for use in a pressure lubricating system of the type referred to above, and which shall be so constructed that it can be operated from the link mechanism of the locomotive valve gear.

It is a further object of this invention to produce a pump mechanism of a simple and substantial construction that can be cheaply manufactured and which will be positive in its operation and which will not readily become disarranged.

The above and other objects that may become apparent as this description proceeds are attained by means of a construction and arrangement of parts that will be described in detail, and reference for this purpose will now be had to the accompanying drawing in which the preferred embodiment has been illustrated and in which:

Fig. 1 is a side elevation showing one of the drive wheels of the locomotive and a part of the frame work and showing also the improved lubricator in place thereon;

Fig. 2 is a section taken on line 2—2, Fig. 1;

Fig. 3 is a section taken on line 3—3, Fig. 2; and

Fig. 4 is a section taken on line 4—4, Fig. 2;

In the drawing numeral 1 represents a 55 drivewheel of a locomotive and numeral 2 one of the frame members to which the cross-head guides 3 are connected. Numeral 4 represents another part of the locomotive frame, while numeral 5 represents one of the links forming part of the valve gear of the engine. This link is rocked whenever the engine operates and this in turn causes the shaft 6 to oscillate about its axis. Secured to the end of shaft 6 is a crank arm 7 60 to which reference will be made hereinafter. Each wheel is provided with a flange 8 that engages the side of the rails for the purpose of keeping the locomotive on the track in a manner well understood. In going around 70 curves there is usually a great pressure between the flange and the side of the rail which is objectionable for reasons already given. It has been found that it is necessary for the best operation of the engine to lubricate 75 the flanges as this will reduce the wear and also eliminate the danger of the wheel climbing the rail so as to derail the locomotive.

For the purpose of positively lubricating 80 the flanges whenever the engine is running, a very simple mechanism has been provided, which will now be described.

This mechanism consists of a container 9 which is supported on the horizontal arm 10 85 of a bracket, whose vertical arm 11 is secured to the stationary frame member 2. The construction of this container and the mechanism connected therewith has been illustrated in Figs. 2, 3 and 4 from which it will be seen 90 that the container is a rectangular cast-iron box provided at each corner with a lug 12, which is perforated for the reception of a bolt by means of which it is secured to the horizontal arm 10. A cover 13 is provided on 95 one side with lugs 14 that cooperate with lugs 15 on the casing to form a hinge. These lugs are connected by means of hinge pins 16 in the manner shown in Fig. 4. The other side of the cover is provided with a lug 17 100

and directly beneath this are two lugs 18, between which is pivoted a loop 19, which is adapted to receive the end of the lug 17 so as to form a lock or a latch for the purpose of holding the cover in closed position. A bolt 20 passes through the upper end of the loop 19 and engages the lug so as to produce the necessary downward pressure to hold the cover in closed position. A shaft 21 extends transversely through the casing and is journalled in bearings 22 and 23. The bearing 22 is formed in a manner shown in Fig. 2, while bearing 23 is constructed with a gland or packing box, whose plug member has been indicated by reference numeral 24. The outer end of the shaft 21 has secured to it an upwardly extending arm 25 that is provided with a number of openings 26. A connecting rod 27 extends between the arm 7 and arm 25 in the manner shown in Fig. 1, so that whenever the shaft 6 is oscillated, this motion will be conducted by means of the connecting rod to the shaft 21. The extent of the oscillation of shaft 21 can be regulated to some extent by connecting the ends of the connecting rod 27 at different distances from the center of rotation of the shaft 6 and shaft 21. From the above description it will be apparent that shaft 21 will only oscillate whenever the locomotive is moving.

For the purpose of utilizing this oscillatory motion of shaft 21 for feeding lubricant, shaft 21 is provided with a crank arm 28 to the outer end of which a short connecting rod 29 is pivotally connected. The other end of this connecting rod is located between the ends 30 of two parallel spaced plungers 31, and is pivotally connected with this by means of a pivot pin 32. The bottom of the casing 40 is provided with a solid block 33, which has been shown as formed integral with the casing, but which may be made of a separate piece, if desired. This block is provided with two parallel cylindrical openings 34. Plugs 35 are inserted into the ends of these openings in the manner shown in Fig. 3. The inner ends of plugs 35 are provided with axial openings 36 for the reception of the pistons 37 which are formed by a reduced section of the plungers 31. Holes 38 extend downwardly through the block 33 and intersect the openings 36. A transverse opening 39 connects the two vertical openings 38 in the manner shown quite clearly in Figs. 2 and 4. By the construction shown opening 34 may be made of the same diameter throughout which make it possible to drill it from the outside inwardly, thereby reducing the expense and labor over what would be required if the two openings, 34 and 36, of different diameters were to be formed in a solid block. The use of removable plugs 35 for closing the outer ends of openings 34 and providing the inner ends of these plugs with axial cylindrical openings with which the

pistons or plungers 37 cooperate makes it possible to replace the plugs when the sides of openings 36 become worn and also makes it possible to vary the capacity by merely making the opening 36 and plunger 37 of different diameters.

At the bottom of the cylindrical openings 36, vertical openings 40 are provided. These connect with horizontal openings 41 to the outer ends of which tubes 42 are connected in the manner shown in Figures 2 and 4. The vertical openings 40 are of two diameters, the upper section of each being larger than the lower section whereby a shoulder is formed which functions as a seat for the ball 43. Screws 44 close the upper ends of the openings 40 and hold the balls in their places. It is apparent that the balls 43 act as check valves which permit the lubricant to flow from the cylinder 26 into the tubes 42, but prevent flow in the opposite direction. When shaft 21 is oscillated plungers 30 will be reciprocated and with the cylinders 36 form a pump. When the parts are in the position shown in Fig. 3, the lubricant may flow into cylinders 36 and when the pistons are moved towards the left, this lubricant will be forced upwardly through the openings 40 into the horizontal openings 41 and will pass from thence into the tubes 42. The length of the stroke of the pistons is determined by the position of the ends of the connecting rod 27 with respect to the arms 7 and 25 in the manner above intimated. Tubes 42 extend from the casing 9 to a place adjacent to where the lubricant is to be applied to the wheels. In the drawing I have shown two plungers and two separate tubes 42, but there may be as many of these as may be desired. The ends of these tubes are connected by means of flexible tubing 46 which extends to an applicator which will not be described in detail.

The flexible tubes 46 are connected to the upper end of pipe 47. A rubber tube 48 is telescopically connected with the lower end of pipe 47 and the end of this tube as well as the end of pipe 47, has been cut diagonally so that a surface is produced which will fit against the surface of flange 8, as the end of tube 48 can be moved downwardly it will therefore serve its purpose until it is almost entirely used up. A check valve 49 is provided in tubes 42 adjacent the place where the flexible tubes 46 are connected with them as indicated in Fig. 1. Since the casing 9 is located on the outside of the locomotive, it is subjected to variations in temperature and it is therefore necessary to provide some means for heating the contents during cold weather. For this purpose we have provided the casing with an opening 50, which extends longitudinally thereof. This opening may be formed when the casing is cast or it may

consist merely of a pipe that can be applied at any time. In the construction shown the opening 50 is cored when the casing is cast and pipes 51 and 52 are secured to opposite ends of this opening. Pipe 51 may be connected with the steam dome of the locomotive boiler or to any pipe containing live steam so that there will be a constant flow of steam through the opening 50. The steam flowing through opening 50 will produce sufficient heat to keep the oil in a flowable condition during the coldest weather. With the parts assembled in the manner above described, we will now consider the operation 15 of the same.

Let us assume that the casing 9 is filled with a lubricating oil and that the engine is in operation. During the operation of the engine shaft 6 will oscillate, thereby oscillating shaft 21 so as to reciprocate the plungers. The reciprocation of the plungers in the cylindrical openings 36 produces a pump action that forces the lubricant through the pipe 42, through the flexible tubes 48 and 25 through the pivoted pipe 47 of the applicator. This lubricant emerges from the lower end of pipe 47 and is deposited directly onto flange 8. The nonmetallic tube 48 serves to spread the lubricant evenly over the flange 30 surface and also to produce a tight connection between the flange and thereby prevent the lubricant from flowing during those times when the engine is standing still. The check valve 49 assists the action of the ball 43 35 in the pump so as to make the operation of the pump more positive. It is possible to dispense with the check valves 49 under certain circumstances, but when they are used, they assist in preventing the oil from flowing 40 when the engine remains stationary.

It has been intimated above that as many plungers can be employed as may be desired and therefore the illustration, where only 45 two plungers have been shown, should not be considered as in any way limiting this invention to this number.

From the above it will be apparent that a flange lubricator has been produced that is positive in its operation and which will deliver the lubricant to the flanges at the most 50 suitable place. Since this lubricator has a positive feed, it can be absolutely relied upon to furnish the lubricant in the desired quantities regardless of the atmospheric conditions. Since the operation of this lubricator is dependent upon the operation of the valve 55 link mechanism of the engine, it is apparent that there will be no flow of lubricant when the engine is stationary and that whenever 60 the engine is running, the parts will receive the necessary amount of lubrication.

The check valve 49, as above intimated, serves to prevent siphoning of oil from the container. The nonmetallic tube 48 is supposed to fit closely against the flange, but 65

it sometimes happens that oil will start leaking between the end of tube 48 and the flange and in the absence of the check valve 49, there will be a tendency to siphon the oil from the container. The check valves 49 are merely simple ball check valves of the ordinary type and the weight of the ball is sufficient to prevent the siphoning above referred to.

This application is a division of our co-pending application Serial Number 221,922, filed September 26, 1927.

Having described the invention, what is claimed as new is:

1. A lubricant pump for pressure lubrication, comprising, in combination, a casing adapted to contain oil, a cylinder block formed integral with the bottom and one end of the casing, said block having a cylindrical opening extending the entire length of the block, said block having also a second opening parallel with and spaced from the first mentioned opening, said second opening extending only partly through the block, the second opening lying above the first mentioned opening, said block having a passage 80 connecting the inner end of the second opening with the first mentioned opening, a check valve in said passage, a plug located in the outer end of the opening and extending inwardly beyond the passage containing the 85 check valve, the inner end of said plug having an axial opening and a lateral opening connecting the opening in the plug with the passage containing the check valve, a piston located in the inner end of the first mentioned 90 opening, the end of the piston having a plunger of smaller diameter which extends into the opening in the plug, said plug and block having a passage communicating with the interior of the casing, a shaft extending transversely of the casing and journalled in the sides of the casing, a crank arm carried by the shaft, and a connecting rod for connecting the plunger with the crank whereby the plunger will be reciprocated when the shaft 95 is oscillated.

2. A lubricant pump for pressure lubrication comprising, in combination, a casing adapted to contain a lubricant, a cylinder block terminating within the casing and formed integral therewith, said block having a plurality of openings extending entirely through it from the outside of the casing to the inner end thereof, a plug extending inwardly into each opening, the inner end of each plug having an axial opening in its inner end, the block having also a plurality of openings extending inwardly from the outer end thereof, said openings lying directly above the first mentioned openings and spaced from the latter, a passageway connecting each of the last mentioned openings with the opening in the plug located in the corresponding first mentioned opening, a check valve in each of said passageways, said block having an un- 100 105 110 115 120 125 130

obstructed passageway from the inner end of the opening in each plug to the interior of the casing, a piston mounted for reciprocation in each of the first mentioned openings, each 5 piston having its end provided with a plunger adapted to fit the opening in the corresponding plug, a shaft extending transversely of the casing and journaled in the sides of the casing, a crank arm secured to the shaft, 10 and a connecting rod having one end pivotally connected with the inner ends of the pistons and the other end connected with the crank arm whereby, when the shaft is oscillated the pistons will be reciprocated, the extent of said reciprocations being less than the 15 length of the openings in the plugs.

In testimony we affix our signatures.
